HARDWARE PACKAGE FOR CORNER BRACES AND THE LIKE

Rome C. Seyforth, Shelby, Ohio, assignor to The Shelby Metal Products Company, Shelby, Ohio, a corporation of Ohio

Application October 30, 1956, Serial No. 619,193

4 Claims. (Cl. 206—79)

This invention relates to a package for items of hardware on the order of corner braces, that is, in being generally elongated and in having angularly related contiguous portions. More particularly, the invention is concerned with a display card type of package in which such items are held assembled with a plurality of fastening elements for use with the same.

A prior type of package used for a similar purpose consisted of a comparatively small card to which two nested corner braces were attached such that corresponding legs of the braces extended outwardly from the face of the card and a plurality of screws similarly projected from such card face. This arrangement, while supplying braces and screws as a functional unit for individual purchase, was not particularly well-suited for display in counter boxes or on shelves since the package would not lie flat. Moreover, the projection of the parts, especially the screws, often caused the package to become snagged in handling, for example, with other similar packages in a counter display.

It is a primary object of the present invention to provide a display package of the type in question which is free of the above-noted disadvantages. More specific objects are to provide such a package which may be laid perfectly flat on a counter or shelf, if this be the means of display; to guard the screws, without employing a separate bag attached to the package or other added pieces; and to provide such an improved package at a reasonable cost.

The latter, very practical, objective involves the further considerations of ease of manufacture of the components used other than the hardware itself, the cost of such components, and the labor needed to assemble the package. My improved package is especially economical in these respects.

Other objects and advantages of the present invention will become apparent as the following description proceeds.

To the accomplishment of the foregoing and related ends, the invention, then, comprises the features hereinafter fully described and particularly pointed out in the claims, the following description and the annexed drawing setting forth in detail a certain illustrative embodiment of the invention, this being indicative, however, of but a few of the various ways in which the principle of the invention may be employed.

In said annexed drawing:

Fig. 1 is a plan view of a blank from which the card of my new package is formed;

Fig. 2 is a front view of a completely assembled package;

Fig. 3 is a sectional view taken on the plane of the line 3—3 in Fig. 2; and

Fig. 4 is a section taken on the line 4—4 in Fig. 2.

Referring now to the drawing in detail, it is believed that the nature of the new package and its advantages may best be described by setting forth the manner of assembly of the various components, commencing with

2

the blank shown in Fig. 1. This blank is a single piece of cardboard or the like cut to the particular shape illustrated, so as to comprise a substantially square major section 10, a lateral extension 11 of reduced width at 5 one margin, a second extension 12 at an adjacent margin of the main section 10, and a minor rectangular section 13 at the outer end of the extension 12.

Section 13 is as wide as the major section 10 but of less length, as measured in the direction of the lateral extension 12 which serves to bridge or connect the major and minor sections. The major section 10 is cut along lines 14 and 15 to provide inwardly penetrating portions of the extensions 11 and 12, respectively, and such penetration is slightly larger than the edge width of two corner braces in nested relation.

Extension 11 is provided with an inner fold line 16 at the ends of the cuts 14, two comparatively closely spaced fold lines 17 outwardly of the line 16 a predetermined distance, and an outer fold line 18 at approximately the 20 same spacing from the lines 17 as the inner line 16. The extension 12 is similarly provided with an inner fold line 19, two intermediate lines 20, and a line 21, the latter being at the junction between such extension and the minor section 13. All of these fold lines are transverse and formed in any suitable manner, for example, by stamping of the material.

As noted previously, the penetration of the extensions 11 and 12, which are oriented at right angles, is approximately the edge width of two nested corner braces; the 30 lines 17 of the former and lines 20 of the latter are spaced apart approximately the same distance, while the distance from each such pair of lines to the two end fold lines in each series is approximately equal to the width of the legs of the braces. The blank is provided with a plurality of holes, a hole 22 being located in the outer end portion of extension 11, two holes 23 being formed in the minor section 13 adjacent the outer edge of the same, and the major section 10 having holes 24 laterally spaced apart the same as the holes 23 and a 40 series of holes 25 arranged, in this particular package, in two rows of four each.

As shown in Fig. 2, this package includes two conventional corner braces 26 and eight screws 27, each brace having the usual two openings 28 in each leg for fastening of the same by means of the screws. Assembly of 45 the package is indeed simple and requires only one other component, namely, a thin flexible metal strip capable of forming a staple 29.

In the assembly procedure which is preferred for its convenience and speed, the blank is laid against one face 50 of a rectangular block, not shown here, having drilled holes in one corner area which correspond in spacing and arrangement to the holes 24 and 25 in the section 10 of the blank. The thickness of the block is equal to the width of the corner braces. The main section 10 of the 55 blank is arranged with its holes in registry with the drilled holes of the block, and in this condition the fold lines 16 and 19 of the two side extensions will be positioned at adjacent block edges. The extensions are then folded downwardly about the lines 16 and 19 to lie against the 60 side faces of block, and the two corner braces are disposed about the block corner overlying these portions of the extensions, that is, the portions between the inner and intermediate fold lines in each case. The eight screws 27 are next inserted through the holes 25, the drilled holes 65 of the block accommodating the same, the extension 11 is folded back about the corner braces at its side so that its hole 22 is aligned with the hole 24 in the main section of the blank nearest the same, and the minor section 13 is folded back to overlie the screw heads and the extreme end portion of the extension 11. The extension 12 thus similarly is wrapped about the braces at the other legs of

the same, and holes 23 of the section 13 are aligned with the holes 24 in the section 10. The staple 28 is next inserted downwardly through the latter and the complete assembly simply lifted from the block. It is then necessary only to crimp the ends of the staple to complete the job.

In this new package, the corner braces actually rest on edge on the card, but at the margins of the latter due to the cutting back of the band-forming extensions 11 and 12. The two nested braces are securely held to the card at both leg regions and the screws are, of course, held in place by having the heads thereof engaged between the front and back folds of the card as shown most clearly in Fig. 4. Although the screws project from the front face of the card, their height in relation to the width of the braces (Fig. 3) and their disposition within the included angle area of the same is such that the braces act as guards substantially eliminating any possibility of snagging.

It will also be apparent that the package can lie flat on a shelf or counter. Since it may in some instances be desired to hang the package on a rack, the main section 10 is provided with an elongated cut-out 30 for passage of a bracket, such as one of the loop members commonly used with peg-board mounting panels. Since the back fold, or section 13, is not as long as the front panel, the top of the card is of single thickness and only this need be cut for the slot 30. With respect to the feature of guarding the screws with the braces, other arrangements can be employed without loss of the same, for example, the screws could be positioned in a generally triangular array between the legs of the braces.

Briefly, my improved package thus comprises a card to which corner braces or other pieces of angular form and plural fastening elements are firmly attached and fully supported with only one card fastener employed; the plural fastening elements are individually mounted, yet guarded by their particular relation to the braces and the like.

Other modes of applying the principle of the invention may be employed, change being made as regards the details described, provided the features stated in any of the following claims or the equivalent of such be employed.

I, therefore, particularly point out and distinctly claim as my invention:

1. A hardware package comprising a display card having a front panel, two strap-forming extensions at adjacent margins of the same, and a rear panel at the end of one such extension, the connections of both extensions to the front panel being offset inwardly of such margins of the latter; an angular piece of hardware disposed against the front panel of the card with its angularly related portions respectively within such adjacent margins thereof, said extensions being wrapped about such portions with the rear panel and the free end of the other extension brought against the opposite face of the front panel; and a plurality of fastening elements intended for use

4
with the hardware, said elements having heads and being arranged to project through the front panel forwardly and in proximity to the piece of hardware; the heads of the elements being overlain by the rear card panel; and a staple securing the front and rear panels and such other extension together as thus arranged.

2. A hardware package comprising a display card having a front panel, two strap-forming extensions at adjacent margins of the same, and a rear panel at the end of one such extension, the connections of both extensions to the front panel being off-set inwardly of such margins of the latter; an angular piece of hardware disposed against the front panel of the card with its angularly related portions respectively within such adjacent margins thereof, said extensions being wrapped about such portions with the rear panel and the free end of the other extension brought against the opposite face of the front panel; a plurality of fastening elements intended for use with the hardware, said elements having heads and being arranged to project through the front panel forwardly and in proximity to the piece of hardware, the heads of the elements being overlain by the rear card panel; and means securing the front and rear panels and such other extension together as thus arranged.

3. A hardware package comprising a display card having a front panel, two strap-forming extensions at adjacent margins of the same, and a rear panel at the end of one such extension, the connections of both extensions to the front panel being off-set inwardly of such margins of the latter; an angular piece of hardware disposed against the front panel of the card with its angularly related portions respectively within such adjacent margins thereof, said extensions being wrapped about such portions with the rear panel and the free end of the other extension brought against the opposite face of the front panel; and a staple securing the front and rear panels and such other extension together as thus arranged.

4. A hardware package comprising a display card having a front panel, two strap-forming extensions at adjacent margins of the same, and a rear panel at the end of one such extension, the connections of both extensions to the front panel being offset inwardly of such margins of the latter; an angular piece of hardware disposed against the front panel of the card with its angularly related portions respectively within such adjacent margins thereof, said extensions being wrapped about such portions with the rear panel and the free end of the other extension brought against the opposite face of the front panel; and means securing the front and rear panels and such other extension together as thus arranged.
